UNITED STATES PATENT OFFICE

2,195,142

HEATING COIL

Frank E. Bliss, Vancouver, Wash.

Application July 25, 1938, Serial No. 221,245

2 Claims. (Cl. 257—198)

This invention relates to heating coils to be employed in conjunction with heating systems of oil tanks, and has for the primary object the provision of a device of this character which will eliminate the possibility of moisture present in the heating system from reaching the oil and causing boiling thereof and waste due to boiling over of the oil from the tank, consequently rendering a large saving which up to the present time has been excessive to oil companies.

Another object of this invention is the provision of a coil construction which will freely expand and contract under varying temperatures without danger of leakage and admitting moisture to the oil.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a longitudinal sectional view showing an oil tank equipped with a heating coil constructed in accordance with the present invention.

Figure 2 is a vertical sectional view showing the heating coil and its supporting means.

Figure 3 is an enlarged fragmentary vertical sectional view showing one of the supporting racks for the heating coil.

Figure 4 is a fragmentary transverse sectional view showing a portion of one of the racks.

Figure 5 is a side elevation illustrating the heating coil.

Figure 6 is a sectional view taken on the line 6—6 of Figure 5.

Figure 7 is a sectional view taken on line 7—7 of Figure 6.

Referring in detail to the drawings, the numeral 10 indicates a conventional type of oil tank in which oil is to be heated. The cover of the tank is not shown, however, it is supported on the tank by vertically arranged members 11. Also shown on the tank 10 is the usual swing pipe 12 mounted for swinging movement and a windlass is indicated at 13 for the operation of the swing pipe. The foregoing description briefly sets forth an oil tank to which the present invention is adapted.

Arranged in the tank 10 a selected distance from the bottom thereof is a steam heating coil construction 14 consisting of groups of coil pipes 15 each of hairpin formation and each construct-

ed of a single length of tubing or pipe of a selected length. The runs of each coil are superimposed.

Arranged at one end of the groups of coils is an intake header 16 and an exhaust header 17. The headers are arranged in superimposed relation and one slightly laterally of the other, as clearly shown in Figure 2. The intake header is arranged above the exhaust header. The headers are in the form of tubes or pipes and extend transversely of the coils. Supporting legs 18 are welded or otherwise secured on the headers and are equipped with skids 19 to contact the bottom of the tank, consequently mounting the headers for free movement within the tank so that said headers can readily expand and contract without being subjected to undue restraint. The upper runs of the coils connect with the intake header while the lower runs of the coils connect with the exhaust header. The coils are welded onto the headers. The upper runs of the coils slope downwardly from the intake header to prevent condensation from accumulating therein and the lower runs of the coils slope downwardly to the exhaust header to prevent accumulation of condensation in the lower runs. All of the coils connect to the headers above the bottom walls of said headers except the end coil which connects with the headers substantially flush with the bottom walls of said headers. An illustration of this arrangement is made in Figure 7 and the purpose of which is to prevent the accumulation of condensation in the coil.

Relatively spaced racks 20 support the upper and lower runs of the coils as clearly shown in Figure 5. The coils are free to slide on the racks so as not to restrain said coils when expanding and contracting due to varying temperatures. The racks include supporting legs 21 which may be suitably fastened on the bottom of the tank and cross members 22 on which the runs of the coils rest. Mounted on one of the racks and paralleling the cross member 22 thereof is a member 23 of angle iron construction and is provided with notches to receive therein the runs of the coils. The runs of the coils are free to move endwise of the member 23 and crosswise to accommodate expansion and contraction of members 16 and 17. The racks at one side are provided with hook-shaped hangers 24 in which are mounted the runs of the end coil of the group of coils positioning said coil in a plane slightly below the other coils. The runs of the coils being slidably mounted on the racks, said coils may expand and contract without restraint

and through the use of the racks coils of considerable length may be successfully employed. As the coils and headers are free to move under expansion and contraction, the possibility of the coils and the headers breaking is eliminated.

5 Welded to one end of the intake header is a fitting 25 suitably connected and extending through a wall of the tank and equipped with a thermostatic control valve 26 of a conventional construction. The valve 26 connects the fitting 25 to a stream supply pipe (not shown). A fitting 27 is welded to one end of the exhaust header 17 and is suitably connected and extends through a wall of the tank and is equipped with a steam trap 28 arranged exteriorly of the tank and of a conventional construction. Through the use of the valve 26 and the steam trap 28 will permit perfect control of the steam to be had through the coil.

10 20 A steam heating coil of the character described and employed in a heating system and within an oil tank will permit heating of the oil to a desired temperature without danger of moisture reaching the oil and causing the latter to boil. If moisture reaches the oil while heated immediately causes the oil to boil and flow over the tank and thereby bring about a considerable waste of oil and consequently loss in money.

15 25 It is believed that the foregoing description, 30 when taken in connection with the accompanying drawings will fully set forth the construction and advantages of this invention to those skilled in the art to which such a device relates, so that further detailed description will not be required.

Having thus described my invention, what I claim is:

1. A heating coil for oil tanks comprising upper and lower intake and exhaust headers, supporting legs for said headers, skids carried by said legs and resting on a tank to mount the headers for sliding movement, fittings for said headers and secured to and extending through the tank for connecting the headers to a steam heating system, horizontally arranged coils of hairpin shape connecting the headers and each coil having upper and lower runs inclining from the intake header to the exhaust header, racks mounted in the tank and supporting the upper and lower runs of the coils for free sliding movement relative to said racks and one of said coils being supported by the racks in a plane slightly below the other coils and connected onto the headers substantially flush with the bottom walls of the headers.

2. A heating coil for oil tanks comprising intake and exhaust headers arranged in close relation with the exhaust header slightly laterally of the intake header and in a lower plane, a plurality of heating coils of hairpin shape welded onto said headers to permit flow of steam between said headers with condensation freely draining to the exhaust header from the coils and the intake header, supporting legs on the headers and resting freely on a tank to permit the headers to move freely with the expansion and contraction of the coils, racks in the tank and slidably supporting the coils.

FRANK E. BLISS.
